United States Patent Office

Des. 181,693
Patented Dec. 10, 1957

181,693

DISPLAY OF PRINTED REPRODUCTIONS

Harry N. Tichnor, Waban, Mass.

Application June 21, 1956, Serial No. 41,997

Term of patent 3½ years

(Cl. D80—1)

FIG. 1

FIG. 4

FIG. 3

FIG. 2

Fig. 1 is a perspective view of a display of printed reproductions embodying the design of my invention;

Fig. 2 is a front elevation view of Fig. 1;

Fig. 3 is a side elevation view of Fig. 1; and

Fig. 4 is a top plan view of Fig. 1.

The dotted line representation is for purposes of illustration only.

I claim:

The ornamental design for the display of printed reproductions, substantially as shown and described.
